UNITED STATES PATENT OFFICE.

ALLEN B. NORTON, OF DETROIT, MICHIGAN, ASSIGNOR TO THE ALUMINUM CASTINGS COMPANY, OF CLEVELAND, OHIO, A CORPORATION OF OHIO.

MOLD.

1,296,594.

Specification of Letters Patent.

Patented Mar. 4, 1919.

Application filed March 9, 1916, Serial No. 83,021. Renewed January 9, 1919. Serial No. 270,440.

To all whom it may concern:

Be it known that I, ALLEN B. NORTON, a citizen of the United States, residing at Detroit, in the county of Wayne and State 5 of Michigan, have invented certain new and useful Improvements in and Relating to Molds, of which the following is a specification.

This invention relates to permanent molds 10 adapted for casting articles from molten metal or metallic alloys, such as aluminum and aluminum alloys; more particularly the present invention relates to the construction of the gate through which the molten metal 15 flows to the mold cavity and the relation thereof to the said mold cavity.

My invention has for some of its objects the provision of an improved gate for a mold adapted (a) to control the flow of metal to 20 the mold cavity to properly fill the same, (b) to feed the metal to the mold cavity in a manner conducive to the proper setting of the casting and tending to prevent porosity in the casting due both to crystallization 25 shrinkage and occluded air or gases and to prevent the entrance of oxids and other foreign materials into the mold cavity.

A further object of the invention is the provision of an improved gate especially 30 adapted to suitably feed the molten metal to an annular or a cup-shaped mold cavity.

Another object of the invention is to provide a mold with a gate of improved construction for controlling the flow of metal 35 into the mold cavity, the mold and gate structure having means for retarding or accelerating solidification of the metal in portions of the mold cavity to insure setting of all part of the castings as desired.

40 Other objects of my invention will be obvious to one skilled in the art from the description of one form of mechanism embodying it, which, for the purpose of illustration, I have, in the accompanying drawings, shown and hereinafter described.

Figure 1 is a top plan view of a mold provided with a gate embodying my invention.

Fig. 2 is a section on the line 2—2 of Fig. 1.

50 Fig. 3 is a fragmentary section on the line 3—3 of Fig. 2.

Figs. 4, 5, and 6 are fragmentary sectional views on the lines 4—4, 5—5, and 6—6, respectively, of Fig. 2.

Fig. 7 is a fragmentary sectional view on 55 the line 7—7 of Fig. 1.

Fig. 8 is a fragmentary section, similar to Fig. 2, showing the pouring of the molten metal.

Fig. 9 shows a casting having a sprue as 60 formed in a mold embodying my invention.

Figs. 10 and 11 are sections on the lines 10 and 11, respectively of Fig. 9.

Referring to the drawings, 1 indicates as an entirety a permanent mold comprising a 65 plurality of parts adapted to be assembled together to form a mold cavity A. In the preferred form of construction the mold consists of a base member 2 and complementary members 3, 4, arranged on the base member 2. The mold members 3, 4, are provided with abutting side walls 5, each of which has a semi-circular portion 5^a adapted, in co-operation with the semi-circular portion 5^a of the wall 5 of the other mold member and 70 the base, to form the outer wall of the mold cavity A. The mold members 3, 4, are movable on the base 2 away from each other to permit the removal of the castings. The base member 2 is preferably supported on 75 feet 2^a.

Each of the mold members preferably comprises, in addition to the wall 5, a bottom wall 6, a top wall 7 and end walls 8, 9, all integrally connected together. These 85 walls project away from the wall 5 and serve to form a chamber 10, the outer side of which is formed by a plate 11. The plate 11 is secured to the end edges of the walls 7, 8, and 9 by bolts 11^a or other suitable devices. The 90 purpose of the chamber 10 will be later described.

12 indicates devices by means of which the mold members 3, 4, are properly positioned on the base 2 and brought into alignment when moved together. The devices 12 may comprise an annular shoulder 12^a on the base 2 and semi-circular recesses 12^b formed in each mold member 3, 4, and adapted to receive the annular shoulder 12^a 100 when the said mold members are moved together, as shown in Fig. 1. As the annular shoulder 12^a and side walls of the recesses 12^b are struck from the same axis, it will be understood that the shoulders exactly fit 105 within the recesses and thus effect the perfect positioning of the mold members.

13 indicates separate alining and position-

ing devices which may be supplemental to or substituted for the devices 12. The devices 13 comprise a pair of fixed pins 13^a arranged near opposite sides of the base 2 and projecting upwardly therefrom, and recesses 13^b formed in the opposing faces of the walls 5. The recesses 13^b are of a size and shape to receive the pins. One half of each recess 13^b is formed in each wall 5 so that when the mold members 3, 4, are moved together the pins fit into the recesses 13^b, and cause the alignment of said members.

14 indicates as an entirety the core which is preferably of the permanent type. The core 14 may be formed of a plurality of sections, not only for convenience in assembling and disassembling, but more especially to provide for projecting members on the inner surface of the casting and the disengagement of the core sections therefrom prior to their removal from the mold. In the preferred form of the construction, the core 14 consists of a center section 14^a and pairs of side sections 14^b. Each of these sections is provided with a handle 14^c.

The lower end of the core section 14^a may be provided with an insert member 14^d to effect suitable venting.

Above the cavity A, the mold members 3, 4, are formed with recesses to receive semi-circular members 14^e. The members 14^e are formed with fine grooves 14^e' on their lower end edges and inner faces. These grooves serve as vents for the cavity A.

14^f indicates core pins which project through openings formed in the sides of the mold members 3, 4. The inner ends of the pins 14^f serve as cores to form openings in bosses of the casting.

15 indicates as an entirety devices for locking the mold members 3, 4, together. These devices serve to maintain the mold members in rigid relationship during casting, the opposing faces of the walls 5 being surfaced to fit tightly together. The locking devices 15 may be of any suitable character, but in the construction illustrated, they consist of a pin 15^a fixed to one mold member and a hook member 15^b swingably carried by the other member and movable into engagement with the pin 15^a. The hook portion of the swinging member 15^b is preferably provided with a wedge-shaped surface which, acting against the pin 15^a, operates to draw the mold members 3, 4, tightly together. This result may be effected by applying several blows with a hammer or mallet to the swinging member 15^b.

The foregoing described parts or combination of parts, in themselves, form no part of my invention but are, as I believe, the invention of Joseph H. Bamberg of Tonawanda, New York, and I therefore make no claim to the same.

16 As shown in the accompanying drawings,

the cavity A, in the mold 1, is shaped to form a trunk or skirted piston for internal combustion motors; my improved gate is peculiarly adapted to direct and control the flow of the molten metal to a cup-shaped cavity to form a casting having walls of desired physical structure which are substantially non-porous.

The gate is indicated as an entirety at 16 and preferably comprises complementary recesses 16^a, 16^b, formed in the opposing faces of the walls 5, 5. One end of each recess terminates at the upper edge of the adjacent mold member; its other end merges into the mold cavity A. Between their opposite ends, 75 the recesses 16^a are shaped to form the co-operating sections constituting the gate 16 as follows. 16^b indicates the inlet section for the molten metal. This section is substantially funnel or cone shaped, except for a 85 portion of its upper outer wall which is curved laterally, as shown at 16^c to form a convex metal engaging and directing wall or channel. In operation, the molten metal is poured from a suitable ladle B onto the convex wall 16^c which arrests its drop and from which the metal flows or is directed down the adjacent sides of the inlet section 16^b without agitation into a pocket or chamber 16^b' formed at the lower end of the inlet 16^b. 90 The bottom of the chamber 16^b' is rounded and the outer wall of the inlet 16^b merges into the wall of the chamber 16^b' at a point tangential to it so as to avoid the formation of broken or uneven surfaces in the path of 95 100 flow of the molten metal.

16^d indicates a neck section or control passage which leads upwardly in an inclined direction from the pocket 16^b' and co-operates therewith and with the inlet 16^b to form 105 a trap or seal of molten metal. The lower wall of this neck section 16^d at its upper or discharge end, indicated at 16^e, is in a horizontal plane above the upper wall at the inlet end of the neck, as indicated at 16^e'. The 110 neck or control passage 16^d is preferably of the same cross-sectional area from end to end and smaller in cross section than the lower end of the inlet 16^b or the chamber 16^b', so as to choke and control the flow of metal 115 from the chamber 16^b'.

16^f indicates a delivery gate or feeder into which the neck 16^d discharges the molten metal. The delivery gate 16^f preferably is connected by a short, narrow passage or 120 slot 16^g with the mold cavity A at its upper and lower ends and points therebetween. By this construction the molten metal flowing through the gate is fed substantially continually on top of the metal as it rises in 125 the mold cavity until the cavity is completely filled, thereby compensating during the pouring period for any solidification shrinkage occurring during said pouring period; furthermore, substantially all portions of the 130

metal in the cavity are kept in contact with and form an integral part with the metal in the gate. The neck 16^a is connected to the upper end of the feeder 16^f. The purpose of this form of construction is two-fold; first, it permits me to utilize the head of the metal flowing through the neck 16^a to force the metal into the extreme upper end portions of the cavity A and thereby displace all air and other gases within said cavity through the vents 14^e; and second, it provides the necessary head for forcing metal into the lower portion of the mold cavity. In this connection, it will be noted that the upper end wall 16^x of the feeder 16^f is disposed in the same plane as the upper end wall of the mold cavity A, so that the metal from the control passage 16^d must flow in a direct line to the upper portion of the cavity and with sufficient force, as will be later described, to fill the entire cavity. Furthermore, this form of construction permits any air which may be forced into or through the control passage to rise in the feeder and escape through the vents 14^e during the formation of the casting. The connecting wall 16^e between the feeder 16^f and neck 16^a is preferably curved to avoid agitation of the flowing metal; likewise, the outer, downwardly extending end wall of the feeder is inclined from its point of connection with the wall 16^e, as indicated at 16^h and then curved inwardly, as indicated at 16ⁱ to the point where it connects tangentially with the lower end wall of the cavity A, as shown at 16^j, likewise to avoid agitation of the metal as it flows into the mold.

As shown in the drawing, the head of the piston is formed in the lower part of the cavity A so that that portion of the cavity requires a larger quantity of metal than the upper portion, particularly where this head has internal ribs or webs; also, as this lower part of the cavity is filled first, the metal therein would under ordinary conditions set prior to the metal in other parts of the cavity. By reason of these facts I provide suitable means for insuring the complete filling of this part of the cavity which at the same time slightly retards the setting action of the metal therein. These means consist in the formation at the lower end of the feeder 16^f of a chamber 17, which is adapted to hold a relatively large quantity of molten metal.

The chamber 17 is formed by making the lower ends of the recesses 16^a deeper, as will be clearly understood from Fig. 6. The body of metal thus provided for is of such size that it will set relatively slowly. The metal in the chamber 17 remains in liquid condition long enough to insure filling of the adjacent parts of the mold cavity and assists in retarding the setting action of the metal in the lower part of the mold cavity

while the cavity is being completely filled. The body of liquid metal in the cavity 17 serves to prevent shrinkage in the casting adjacent thereto before it sets.

Where my improved gate is used in a permanent mold, heated during the casting operation, I am enabled to utilize to advantage the heat applied to the mold among other things to assist in maintaining the metal in a fluid state while flowing through the gate 70 16. The heating means preferably comprise one or more burners 18 of suitable construction which are arranged to direct flame jets through openings 11^b in the plates 11 into the chambers 10. The chambers 10 serve as 80 ovens to retain the heat from the burners and to effect substantially uniform heating of the walls 5, 5^a.

The burners 18 are preferably arranged to direct their jets against those portions of 85 the walls 5 in which the gate 16 is formed, it being desirable to retard cooling of the molten metal while passing through the gate to the mold cavity A, and to utilize the direct effect of the burners to the best advantage.

To provide for proper filling of the lower part of the mold cavity A, where a considerable quantity of metal is required therefor, the opening 16^s from the feeder 16^f to 95 the cavity is preferably enlarged, as shown at 16^s.

In permanent molds, wherein my invention is most advantageously applied, the air and other gases in the mold cannot escape 100 in any way except through vents and these vents must necessarily be restricted in size to prevent the escape of metal and as much as possible the formation of fins and lugs. My invention is designed to direct the molten metal to the cavity A without undue agitation of the metal, either because of air and other gases sucked through or trapped in the gate, or of the formation of air and gas bubbles in the metal being cast, or the 105 mechanical agitation of the molten metal, as may be caused by splashing. For these reasons the walls forming the inlet, neck and feeder sections of the gate are curved and connected at their adjoining ends in a 110 manner to avoid uneven surfaces so as to insure, in so far as possible, non-agitated flow of the molten metal.

The trap formed by the seal in the conduit 16^a and the lower end of the inlet 16^b serves 120 to exclude from the metal flowing through the neck 16^a substantially all air and other gases which may be drawn downward with the metal into the inlet 16^b; and what little air and other gases may pass with the metal 125 through the neck 16^a, is practically certain to be freed as the metal turns the corner at 16^a, and such air and other gases then escape through the vents 14^e.

The feeding of the molten metal on top of 130

the metal rising in the cavity and feeder from the neck section 16^a, as has already been described, is advantageous for the further reason that it keeps the top of the rising metal in a fluid state; thus, in the event any air and other gases are carried into the cavity, they may free themselves by rising and passing off through the vents 14^c.

From the foregoing description it will be seen that my improved gate serves to feed molten metal to the mold cavity with minimum agitation and substantially free from air and other gases introduced during the pouring operation, thereby materially assisting in reducing porosity in the casting.

It will also be seen that the inlet 16^b, extends upwardly above the discharge end of the neck 16^a a sufficient distance and is large enough to hold a relatively large amount of metal, the weight of which will serve to force the metal through the neck with considerable pressure. When the cavity A is nearly filled with metal, this pressure is utilized to advantage to cause the metal to flow directly from the neck 16^a into the upper portion of the cavity with sufficient force to displace the air and other gases and fill the entire cavity.

It will also be noted that the setting of the casting will take place progressively from a point opposite the gate toward the gate simultaneously at opposite sides of the casting, and that during this setting the molten metal in the gate will compensate for crystallization shrinkage in the casting proper. In this connection the short passage 16^c, between the mold cavity and the feeder section of the gate, performs an important function. For by making this passage short and narrow, and preferably rounding or beveling its side walls as shown in Figs. 5 and 6, it is insured that all metal in said passage, by reason of its proximity to the metal in the gate, shall be maintained at a higher temperature than the metal in the mold cavity and will therefore solidify later than the metal in said cavity and earlier than the metal in the gate. If the metal in the connecting passage 16^c were to freeze before the metal in the mold cavity proper it would draw on the latter metal as well as the gate metal to make up for its crystallization shrinkage. Again, if the metal in said passage 16^c were to freeze after that in some cross section between it and the gate inlet, the metal in the gate between said passage and said cross section would have to make up for its crystallization shrinkage by drawing on the metal in the passage and this would or might cause porosity in the metal of the casting proper adjoining its junction with the gate. The beveling or tapering of the side walls of the passage above referred to causes said walls to be

more highly heated by the molten metal entering the mold cavity, thus helping to insure that the metal occupying the passage at the end of the pouring shall be maintained molten longer than the metal in the cavity proper.

I believe that progressive setting of the metal in the casting is one of the important factors in reducing shrinkage porosity or cracks, or defective castings, and I have had in mind in this invention to have the setting take place progressively with that object in view. It is my opinion that when any liquid metal becomes completely surrounded with solid metal, during freezing, its solidification will be accomplished by a contraction of about three to six per cent. of its total volume, porosity accordingly resulting. In my improved process the gate is so constructed with relation to the mold cavity that at no time is liquid metal allowed to be isolated in any part of the casting, during the greater portion of the solidification period. At substantially all times during the solidification period, the portions of the freezing metal still liquid are in communication with a source of liquid metal from the gate, so that cavities which would normally form by crystallization shrinkage in the casting are filled up.

It will be seen that by means of my improved form of mold I control the flow of molten metal into the mold cavity by changing the direction and velocity of flow of the metal intermediate the mold cavity and the initial pouring point in such manner as to control the velocity and direction of the stream of metal as it enters and fills the mold cavity, so as substantially to (a) preclude splashing or interrupted stream action of the metal into the mold cavity, (b) cause the metal as it flows and before it reaches the mold cavity itself to establish a liquid seal for trapping out from the mold cavity air and other gases, oxids and other foreign materials, and (c) so direct the stream of flowing metal toward remote portions of the mold cavity that the head of molten metal will be utilized to give the desired momentum and direction of flow of metal to such remote portions of the mold cavity to insure the complete filling thereof.

Assuming a given mold cavity having vertical dimensions with portions near the upper end of the cavity somewhat remote from the point at which the metal is to enter the mold cavity, such for example as the cavity A, in the drawings, I have found that in order to have the desired head of metal to assist in completely filling such remote top parts of the mold cavity, the distance from the initial inlet point for pouring to the bottom of the mold will give an undesirable velocity to the metal entering the bottom of

the mold and greater momentum than required to fill the mold at the bottom, besides being likely to cause undesirable splashing and forming of globules at the bottom of 5 the mold as the metal flowing under an unnecessarily high velocity enters the same. Accordingly my process of pouring metal consists, first, in changing the direction and velocity of flow of the metal intermediate 10 the mold cavity and the initial pouring points for the metal. This changing of direction I accomplish by causing the metal to turn a corner, which enables me to slow down its velocity without undue agitation, 15 and at the same time reduces the amount of direct drop of the metal from the initial pouring point on its way to the bottom of the mold cavity. Next I cause the flowing metal itself to form a liquid seal, which 20 liquid seal serves substantially to trap out air and other gases and oxids and other foreign materials and to keep them from entering the mold cavity. By reducing the cross-sectional area of the duct through 25 which the metal flows as it leaves this liquid seal, I can further reduce the velocity with which it enters the bottom of the mold cavity.

Preferably I direct the stream of flowing 30 metal as it leaves the said seal generally toward the upper remote portions of the mold cavity, but for the purpose of directing it into the bottom of the mold cavity I then cause the metal for the bottom of the casting 35 to turn another corner and after it has turned this corner to flow down a gradual incline and thence in a substantially continuous and uninterrupted stream into the mold cavity, it being understood that this 40 last incline should preferably be such as to preclude the flowing metal, under the action of gravity, from dropping in such a manner as to break up into streams or globules, and should merge with the upper wall of the 45 mold cavity on lines substantially tangential thereto, thus insuring that the metal will enter the bottom of the cavity and rise in it substantially without splashing or interrupted stream action. As the flowing metal 50 approaches the top of the mold cavity I make use of the head of molten metal between its initial pouring point and the top of the mold cavity to give the desired momentum of flow to the metal for the more 55 remote upper parts of the mold cavity which metal will be directed toward them by the direction of its flow as it leaves the said hydraulic seal, so as to insure the complete filling of the upper and more remote 60 parts of the mold cavity.

After the seal of the molten metal is formed the molten metal poured into the mold engages the metal in the seal in such manner as (a) to preclude splashing and

formation of globules and (b) to trap out 65 air and other gases, and oxids and other foreign materials.

Referring more specifically to the drawings, the procedure in the use of the mold is as follows:

First, the metal is directed downwardly from a suitable ladle B on the convex wall 16^e of the gate. Thence the metal flows downward in a smooth, non-agitated stream so that it fills the chamber 16^v and, rising 75 in the neck 16^a, forms a liquid seal. Then from the discharge end of the neck 16^b, which is relatively constricted and acts to reduce the velocity of the flow, which has already been somewhat reduced by the 80 change of direction in the section 16^b, the metal flows over the curved wall 16^e and thence downwardly over the inclined wall 16^h and the curved transition wall 16^h whence it moves into the bottom of the mold cavity 85 proper along lines substantially parallel to the bottom wall thereof. The metal thus inducted into the bottom of the mold cavity flows smoothly and in an unbroken stream or mass so that occlusion of air or gases is 90 avoided. As the metal rises in the bottom section of the mold cavity the air above it moves upward into the side sections of the cavity and thence through vent passages surrounding the core to the atmosphere, or 95 such air above the rising metal passes directly into the vent passages in the lower part of the core and thence upward and out to the atmosphere. Then as the metal rises in the side sections of the mold cavity the 100 pouring is preferably continued at a moderate rate such that the metal does not rise materially in the inlet section 16^b. Consequently the metal is discharged from the neck 16^a at a moderate velocity and flows 105 smoothly into the metal which is gradually rising in the feeder section 16^c and thence from the upper part of said metal into the cavity proper. As the level of the metal in 110 said feeder section and the mold cavity approaches the level of the wall 16^e, the pouring is continued at a rate such that the metal rises higher in the inlet section 16^b so that the resulting pressure head, added to the velocity head of the entering metal, insures 115 the discharge of the metal from the neck 16^a at a higher pressure and a consequent complete filling of the upper part of the mold cavity. At the end, the pouring of the metal 120 into the inlet 16^b is continued until the gate 120 is filled substantially up to the convex wall 16^e.

The existence of a eutectic in an alloy for casting purposes is peculiarly advantageous in reducing the amount of porosity in the 125 casting, particularly where the liquid portions of the freezing metal are in direct communication with other liquid metal, for in-

stance in the gate, as provided by my invention, thus permitting the crystallization shrinkage to be filled up or to be taken care of from the molten metal in the gate. 5 As hereinbefore stated, at substantially no time during freezing is any liquid metal isolated from other liquid metal by solid portions.

To those skilled in the art, many modifications of and widely differing embodiments and applications of my invention will suggest themselves, without departing from the spirit and scope thereof. My disclosures and descriptions are purely illustrative and are 15 not intended to be in any sense limiting.

Reference has been made above to the importance of the short, narrow passage 16^g between the feeder section of the gate and the mold cavity proper. A further advantage incident to this narrow passage may 20 here be noted, namely, that it insures the forming of a relatively narrow section of metal between the gate and the casting, which facilitates the removal of the gate 25 from the casting proper.

While I have shown this port of communication between the gate and the mold cavity to extend from the bottom to the top of the mold cavity, it will be understood that it 30 does not necessarily have to extend the entire length of the mold cavity in an unbroken line so long as it does extend to the top of the mold cavity and has sufficient area between the top of the mold cavity and 35 the bottom of the mold cavity to fill the mold cavity progressively from the bottom upwardly by continually introducing metal on top of that which has already entered the mold cavity until the top of the cavity 40 is finally reached.

It will be understood that among the impurities which the liquid seal between the inlet and discharge neck will serve to trap out are those having a lower specific gravity 45 than the metal which is being poured and which are insoluble in the metal.

What I claim is:

1. A gate for a mold cavity comprising a downwardly extending inlet, an upwardly extending discharge neck connected at its lower end to the lower end of said inlet and coöperating therewith to form a liquid seal to oppose the passage of air, gas, oxid and other impurities, and a feeder extending 55 from the upper and discharge end of said neck to the bottom of the mold cavity.

2. A gate for a mold cavity comprising a downwardly extending inlet, an upwardly inclined discharge neck connected at its lower end to the lower end of said inlet and coöperating therewith to form a liquid seal, and a feeder into which the upper end of 60 said neck delivers the molten fluid, said feeder being connected to the mold cavity,

from its lower end wall to its upper end 65 wall.

3. A gate for a mold cavity comprising a downwardly inclined inlet, an upwardly inclined discharge neck connected at its lower end to the inlet and coöperating therewith to form a hydraulic seal, and a feeder into which the upper end of said neck delivers the molten metal, said feeder being connected to the mold cavity from its lower end wall to its upper end wall by an opening 75 smaller in width than said feeder.

4. A gate for a mold cavity comprising a downwardly extending inlet, an upwardly inclined discharge neck connected to the inlet and coöperating therewith to form a hydraulic seal, and a feeder into which the upper end of said neck delivers the molten metal, said feeder being connected with the mold cavity at its lower and upper end walls by a port smaller in width than said feeder 80 and being formed with recesses in its opposite side walls to hold a relatively large body 85 of metal during the pouring thereof.

5. A gate for a mold cavity comprising a downwardly extending inlet, an upwardly 90 inclined discharge neck connected to the inlet and coöperating therewith to form a hydraulic seal, and a feeder into which the upper end of said neck delivers the molten metal, said feeder being connected with the mold cavity at its lower and upper end walls by a port smaller in width than said feeder 95 and being formed near its lower end with recesses in its opposite side walls to hold a relatively large body of metal during the pouring 100 thereof.

6. A gate for a mold cavity comprising a downwardly extending inlet, and an upwardly inclined discharge neck connected together and coöperating to form a liquid seal, and a feeder to which the upper end of said neck delivers molten metal, said feeder having a downwardly inclined wall over which the molten metal flows from said neck to the lower end of the mold cavity. 110

7. A gate for a mold cavity comprising a downwardly extending inlet, and an upwardly inclined discharge neck connected together and coöperating to form a liquid seal, said neck being of smaller cross-sectional area 115 than the lower end of said inlet, and a feeder with which the upper end of said neck communicates and which itself opens into the lower part of the mold cavity.

8. A gate for a mold cavity comprising a 120 downwardly extending inlet, an upright feeder adjacent one side of the mold cavity and adapted to feed the molten metal into said cavity at successively higher levels as the cavity fills, and a laterally extending intermediate section between the inlet and feeder adapted to retard the flow of the molten metal. 125

9. A gate for a mold cavity comprising a downwardly extending inlet, an upwardly inclined discharge neck and a chamber between the adjacent ends of said inlet and neck, the inlet, neck and chamber being connected by uninterrupted smooth walls and coöperating to form a liquid seal. 65
10. A gate for a mold cavity comprising a downwardly extending inlet, an upwardly inclined discharge neck and a chamber which coöperate to form a liquid seal, said chamber having a curved wall to which the outer walls of the inlet and neck are connected tangentially to avoid uneven surfaces over 70 which the molten metal flows. 15
11. A gate for a mold cavity comprising a downwardly extending inlet, a feeder connected to the mold cavity to deliver molten metal thereto progressively from the bottom 20 to the top thereof, and a neck extending upwardly in an inclined direction from the lower end of the inlet to the upper end of the feeder, whereby the molten metal is delivered on top of the metal in the cavity as 25 it rises therein. 25
12. A gate for a mold cavity comprising a downwardly extending inlet, a vertically extending feeder connected to the mold cavity to deliver molten metal thereto progressively from the bottom to the top thereof 30 and having a curved wall over which the metal flows, and a neck extending upwardly in an inclined direction from the lower end of the inlet to the upper end of the feeder, whereby the molten metal is delivered on 35 top of the metal in the cavity as it rises therein. 35
13. A gate for a mold cavity comprising a downwardly extending inlet, a feeder vertically disposed at one side of said mold cavity, and an upwardly inclined neck extending from the lower end of said inlet to the upper end of the feeder, the feeder being connected to the mold cavity at the bottom 40 and top thereof, whereby the molten metal is delivered on top of the metal in the cavity as it rises therein substantially free from air and gases and oxids and other impurities. 45
14. A gate for a mold cavity comprising a downwardly extending inlet, a feeder vertically disposed relatively to said mold cavity, and an upwardly inclined neck extending from the lower end of said inlet to the 50 upper end of the feeder, the feeder being connected to the mold cavity at the bottom and top thereof, the upper wall of the feeder extending directly from the upper end of said neck to the upper end of the mold cavity, whereby the molten metal is delivered on top of the metal in the cavity as it rises 55 therein. 60
15. A gate for a mold cavity comprising a downwardly extending inlet, a feeder vertically disposed along one side of said mold cavity, and an upwardly inclined neck extending from the lower end of said inlet to the upper end of said feeder, the feeder being connected to the mold cavity from end to end thereof and the upper end wall of the feeder being disposed in the plane of the upper end wall of the mold cavity, whereby the molten metal is delivered on top of the metal in the cavity as it rises therein. 65
16. A gate for a mold cavity for a cup-shaped article comprising a downwardly extending inlet, a feeder vertically disposed at one side of said mold cavity, an upwardly inclined neck extending from the lower end of said inlet to the upper end of said feeder and coöperating with the inlet to form a trap, said feeder being connected to the mold cavity from end to end thereof and said inlet extending upwardly above the connection of the neck with said feeder, 70 whereby the neck will cause the metal flowing therefrom under the pressure due to the weight of the metal rising in the inlet during pouring, to fill entirely the mold cavity with metal. 75
17. A permanent mold comprising sections having walls adapted to abut together, said walls being shaped to form a cavity and formed with complementary recesses arranged to provide a gate comprising a downwardly extending inlet, an upwardly inclined discharge neck coöperating with the inlet to form a liquid seal, and a feeder connected at its upper end with the upper end of said discharge neck, vertically disposed 80 relatively to said mold cavity and communicating therewith along one side thereof. 90
18. The combination with a permanent mold comprising sections having walls adapted to abut together, said walls being shaped to form the outer wall of a cavity for a piston having a head and a skirt, and a permanent core arranged to form the inner wall of the cavity, of a gate comprising a downwardly extending inlet, an upwardly inclined discharge neck coöperating with the inlet to form a liquid seal, and a vertically disposed feeder connected at its upper end with the upper end of said neck and communicating with said mold cavity along 95 one side thereof. 100
19. The combination with a permanent mold comprising sections having walls adapted to abut together, said walls being shaped to form the outer wall of a cavity for a piston having a head and a skirt, and a permanent core forming the inner wall of the cavity, of a gate having a downwardly extending inlet, an upwardly inclined discharge neck coöperating with the inlet to 110 form a liquid seal, and a feeder connected at its upper end with said neck, formed in the abutting walls of said mold sections, 115

and communicating with said mold cavity along one side thereof.

20. The combination of a permanent mold comprising sections having walls adapted to abut together, said walls being shaped to form the outer wall of a cavity for a piston having a head and a skirt, and formed with complementary recesses arranged to provide a gate comprising a downwardly extending 5 inlet, an upwardly inclined discharge neck coöperating with the inlet to form a liquid seal, and a feeder connected at its upper end with said neck and communicating with said mold cavity along one side thereof, and 10 a permanent core arranged to form the inner wall of the cavity and about which said feeder directs metal progressively from the bottom to the top of said cavity.
21. The combination of a permanent mold 15 comprising sections having walls adapted to abut together, said walls being shaped to form the outer wall of a cavity for a piston having a head and a skirt, and formed with complementary recesses arranged to provide a gate comprising a downwardly extending inlet, an upwardly inclined discharge neck coöperating with the inlet to form a liquid seal, and a feeder connected at its upper end with the upper end of said 20 neck and communicating with said mold cavity along one side thereof, and a permanent core arranged to form the inner wall of the cavity, and means for directing heat against the portions of the abutting walls 25 in which the gate recesses are formed.

22. The combination of a permanent mold comprising sections having walls adapted to abut together, said walls being shaped to form the outer wall of a cavity for a piston 30 having a head and a skirt, and formed at one side of the cavity walls with complementary recesses arranged to provide a gate comprising a downwardly extending inlet, an upwardly inclined discharge neck coöperating 35 with the inlet to form a liquid seal, and a feeder connected at its upper end with the upper end of said neck and disposed to feed molten metal progressively from the bottom to the top of said cavity, 40 and a permanent core arranged to form the inner wall of the cavity.

23. A permanent mold comprising complementary sections having walls adapted to abut together, said walls being shaped to 45 form the outer wall of the mold cavity and being formed at one side of said cavity with complementary recesses constituting a gate having a downwardly extending inlet, an upright feeder adjacent the mold cavity and adapted to deliver molten metal into said cavity at successively higher levels as the cavity fills, and a laterally extending intermediate section between the inlet and feeder adapted to retard the flow of the molten 50 metal.

24. A gate for a mold cavity comprising a downwardly extending inlet section, an upright feeder adjacent one side of the cavity and formed with a curved wall substantially tangential to the bottom wall of the mold cavity, and a laterally extending intermediate section between the inlet and feeder adapted to retard the flow of the entering metal. 70

25. A gate for a mold cavity comprising a 75 downwardly extending inlet section, an upright feeder adjacent one side of the mold cavity, said feeder having a wall inclined downward toward the bottom of the mold cavity and a curved wall substantially tangent at its upper and lower ends, respectively, to the inclined wall and the bottom wall of the mold cavity, and a section between the inlet and the feeder adapted to retard the flow of the entering metal. 80

26. A gate for a mold cavity comprising an upright feeder adjacent one side of said cavity and a short passage joining the feeder to the cavity, the walls of said passage being beveled substantially as and for 85 the purpose set forth.

27. A gate for a mold cavity comprising an upright feeder adjacent one side of said cavity and a short passage narrower than the feeder joining the feeder to the cavity, 90 the walls of said passage being beveled substantially as and for the purpose set forth.

28. A gate for a mold cavity comprising a downwardly extending inlet, an upright feeder adjacent one side of the mold cavity 100 and adapted to feed the molten metal into said cavity at various levels ranging from the bottom to the top of the mold cavity, and a laterally extending intermediate section between the inlet and feeder adapted to 105 retard the flow of the molten metal.

29. A gate for a mold cavity comprising a downwardly extending inlet, an upright feeder adjacent one side of the mold cavity and adapted to feed the molten metal into 110 said cavity at various levels ranging from the bottom to the top of the mold cavity, and an intermediate section between the inlet and feeder adapted to retard the flow of the molten metal. 115

30. A permanent mold comprising complementary sections having walls adapted to abut together, said walls being shaped to form the outer wall of the mold cavity and being formed at one side of said cavity with 120 complementary recesses constituting a gate having a downwardly extending inlet, an upright feeder adjacent the mold cavity and adapted to deliver molten metal into said cavity at various levels ranging from the 125 bottom to the top of the mold cavity, and an intermediate section between the inlet and feeder adapted to retard the flow of the molten metal.

31. A gate for a mold cavity comprising a 130

- downwardly extending inlet section, a section having a downwardly and laterally extending metal-supporting wall formed and arranged to deliver the entering metal into the bottom of the mold cavity on lines substantially parallel to the bottom wall of said cavity, and an intermediate section between the two other sections adapted to retard the flow of the entering metal.
32. A gate for a mold cavity comprising a downwardly extending inlet section, a section having a downwardly and laterally extending metal-supporting wall formed and arranged to deliver the entering metal into the bottom of the mold cavity on lines substantially parallel to the bottom wall of said cavity, and a laterally extending intermediate section between the two other sections adapted to retard the flow of the entering metal.
33. A gate for a mold cavity comprising a downwardly and laterally extending metal-supporting wall formed and arranged to deliver entering metal into the bottom of the mold cavity on lines substantially parallel to the bottom wall of said cavity, and additional walls to form an upright feeder adjacent the mold cavity and a short narrow passage through which the feeder communicates with the mold cavity at various levels, the feeder chamber having all its cross sectional dimensions substantially greater than both the width and the length of the said passage and also than the thickness of the casting sections.
34. A gate for a mold cavity comprising an upright feeder chamber adjacent to the mold cavity and a passage through which the feeder communicates with the mold cavity at various levels between the bottom and the top of the cavity, the said feeder chamber having all its cross sectional dimensions substantially greater than both the width and the length of the said passage and also than the thickness of the casting sections.
35. A gate for a mold cavity comprising a downwardly extending inlet, an upright feeder adjacent to one side of the mold cavity, a transversely extending section leading from the inlet to the feeder, said feeder being adapted to feed molten metal into said cavity at successively higher levels as the cavity fills, and a constricted passage between said feeder and cavity through which the metal flows, the feeder chamber having all its cross sectional dimensions substantially greater than both the width and the length of the said passage and also than the thickness of the casting sections.
36. A pouring gate for a mold cavity comprising a downwardly extending inlet arranged to receive molten metal poured under the action of gravity, an upright feeder adjacent to one side of the mold cavity and adapted to feed the molten metal into said cavity at various levels ranging from the bottom to the top of the mold cavity, and a laterally extending intermediate section between the inlet and feeder.

In testimony whereof I affix my signature in the presence of two witnesses.

ALLEN B. NORTON.
